(57) **CLAIM**

The ornamental design for a white noise machine with light, as shown and described.

DESCRIPTION

FIG. 1 is a perspective view of a white noise machine with light design showing my new design.

FIG. 2 is a front view of the white noise machine with light.

FIG. 3 is a rear view of the white noise machine with light.

FIG. 4 is a left side view of the white noise machine with light.

FIG. 5 is a right side view of the white noise machine with light.

FIG. 6 is a top view of the white noise machine with light; and,

FIG. 7 is a bottom view of the white noise machine with light.

The broken lines shown in the drawings illustrate portions of the article that form no part of the claimed design.
